[57] CLAIM

The ornamental design for a tool for use in installing
and removing casters, as shown and described.

DESCRIPTION

FIG. 1 is a perspective view of a tool for use in installing
and removing casters showing my new design;

FIG. 2 is a perspective view showing the cap in an
exploded view thereof;

FIG. 3 is a front elevational view thereof;

FIG. 4 is a top plan view thereof;

FIG. 5 is a right side elevational view thereof;

FIG. 6 is a left side elevational view thereof;

FIG. 7 is a rear view thereof; and

FIG. 8 is a bottom plan view thereof.

FIG. 1

FIG. 2

FIG. 3

FIG. 4

FIG. 5

FIG. 6

FIG. 7

FIG. 8
